(57) **CLAIM**

The ornamental design for a spray gun, as shown and described.

DESCRIPTION

FIG. 1 is a perspective view of the spray gun showing our new design;

FIG. 2 is a left side elevational view of the spray gun shown in FIG. 1;

FIG. 3 is a right side elevational view of the spray gun shown in FIG. 1;

FIG. 4 is a back side elevational view of the spray gun shown in FIG. 1;

FIG. 5 is a front side elevational view of the spray gun shown in FIG. 1;

FIG. 6 is a top plan view of the spray gun shown in FIG. 1;

FIG. 7 is a bottom plan view of the spray gun shown in FIG. 1; and,

FIG. 8 is a perspective view of the spray gun showing our new design with a paint gun mounted in the spray gun.
The broken lines in the Figures are directed to features that form no part of the claim.

1 Claim, 8 Drawing Sheets
